(57) **CLAIM**

The ornamental design for a magnetic disc storage unit for a computer as shown and described.

DESCRIPTION

FIG. 1 is a front, top and right side perspective view of a magnetic disc storage unit for a computer according to the design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is an enlarged view of the portion shown in the dot-dash line box labeled 8 in FIG. 2;

FIG. 9 is an enlarged front, top and right side perspective view of the portion shown in BOX 9 of FIG. 1, provided for clarity of illustration;

FIG. 10 is an enlarged front, top and right side perspective view of the portion shown in BOX 10 of FIG. 1, provided for clarity of illustration;

FIG. 11 is an enlarged front view of the portion shown in BOX 11 of FIG. 2, provided for clarity of illustration;

FIG. 12 is an enlarged front view of the portion shown in BOX 12 of FIG. 2, provided for clarity of illustration;

FIG. 13 is an enlarged view of the portion shown in the dot-dash line box labeled 13 in FIG. 1;

FIG. 14 is an enlarged view of the portion shown in the dot-dash line box labeled 14 in FIG. 1;

FIG. 15 is an enlarged view of the portion shown in the dot-dash line box labeled 15 in FIG. 1;

(Continued)

FIG. 16 is an enlarged view of the portion shown in the dot-dash line box labeled 16 in FIG. 1;
 FIG. 17 is an enlarged view of the portion shown in the dot-dash line box labeled 17 in FIG. 2;
 FIG. 18 is an enlarged view of the portion shown in the dot-dash line box labeled 18 in FIG. 2;
 FIG. 19 is an enlarged view of the portion shown in the dot-dash line box labeled 19 in FIG. 2;
 FIG. 20 is an enlarged view of the portion shown in the dot-dash line box labeled 20 in FIG. 2;
 FIG. 21 is an enlarged view of the portion shown in the dot-dash line box labeled 21 in FIG. 2;
 FIG. 22 is an enlarged view of the portion shown in the dot-dash line box labeled 22 in FIG. 1;
 FIG. 23 is an enlarged top plan view thereof;
 FIG. 24 is an enlarged view of the portion shown in the dot-dash line box labeled 24 in FIG. 3;
 FIG. 25 is a cross-sectional view taken along line 25-25 in FIG. 8;
 FIG. 26 is an enlarged view of the portion shown in the dot-dash line box labeled 26 in FIG. 9;
 FIG. 27 is an enlarged view of the portion shown in the dot-dash line box labeled 27 in FIG. 10;
 FIG. 28 is an enlarged view of the portion shown in the dot-dash line box labeled 28 in FIG. 11;
 FIG. 29 is an enlarged view of the portion shown in the dot-dash line box labeled 29 in FIG. 12;
 FIG. 30 is an enlarged view of the portion shown in the dot-dash line box labeled 30 in FIG. 6; and,
 FIG. 31 is an enlarged view of the portion shown in the dot-dash line box labeled 31 in FIG. 25.
 The broken lines in the drawings show portions of the magnetic disc storage unit for a computer that form no part of the claimed design. The dot-dash line boxes shown in FIGS. 1 to 3, 6, 9 to 12, and 25 define the enlarged portions shown in FIGS. 8 to 22, 24, and 26 to 31 and form no part of the claimed design.
